APPARATUS FOR PNEUMATICALLY DRAWING OFF GREEN MALT BATCH OR AGGLOMERATION FROM GERMINATING BOXES

August Rothhaeusler, Kulmbach, Bavaria, Germany, assignor to Erste Kulmbacher Actien-Exportbier-Brauerei, Kulmbach, Bavaria, Germany

Application February 20, 1957, Serial No. 641,328

Claims priority, application Germany October 17, 1956

11 Claims. (Cl. 302—50)

This invention relates to apparatus for drawing off green malt from germinating boxes.

Present-day malting procedures employing pneumatic malt processes are carried out mostly in germinating columns which generally, due to a germinating time of throughout eight days, are known and carried out in a corresponding number of germinating boxes independently fermented in straight vessels, with a box malting vessel having a kiln floor with cross slots.

In this the material during a malting period is turned over at least once a day. For this purpose each germinating box is preferably supplied with its own electrical driven turning mechanism extending the width of the box and movable thereover on trucks by means of a cog-wheel driven track.

After each completion of the malting period of a germinating box, this is drawn off to make room for the charging of the malt kiln, aged and germinated green malt for renewed charging with fresh steeped malt. This takes place as a rule preferably by pneumatic means in which a suction nozzle is manually placed in the green malt and constantly during the drawing off also manually fed during the decrease of the batch. This requires a considerable manual expenditure of time and effort which as a daily effort assumes many hours of expensive manual labor.

It is therefore an object of the present invention to provide mechanical means as a reduction in labor and at the same time provide a more efficient operation. The invention contemplates an apparatus or device for pneumatically drawing off the green malt batch in a germinating box by mechanical means without the necessity of manual labor.

It is thus an object of the invention to provide means in the form of an electric motor to operate the spiral conveyors and to mount such motor on a shield or hood and also to provide switching means likewise mounted on the shield to control the operation of the conveyor means.

Another object of the invention resides in the provision of U-shaped struts connected to the upright struts and to the shield to maintain the latter in position.

A still further object of the invention is to provide a cross strut also of U-shape and connected to the side U-shaped struts to additionally brace the shield for rigid support.

Further, an object of the invention is to provide a rubber elastic strip on the bottom edge of the shield to provide a contact element with the bottom of the box. The shield has a lower straight portion rising perpendicularly and merging into a curved surface which latter contacts and is secured to the upright struts which are connected to the means for actuating the apparatus.

Further objects will be apparent from the following description when considered in connection with the accompanying drawing.

A preferred example of the apparatus according to the invention is illustrated in the drawing, in which:

Figure 1 is a longitudinal front elevation of the apparatus,

2

Figure 2 is a cross section through the middle of the apparatus taken on line 2—2 in the direction of the arrows, and

Figure 3 is an end elevation of the apparatus.

5 The suction chamber shield or shell is designated by the numeral 1. This shield 1 is supported and carried from the side trailing or hauling braces or struts 4 with their arm bracket 17 at right angles thereto at the approximate lower third therefrom and is strengthened by 10 means of a U-shaped support 18 provided in the bracket with its back set on one side of the shield. At the upper ends there are provided eyelets or lugs 16 which cooperate with similar lugs of the machine truck and to be connected to the chassis of the machine truck by means of a draw pin or bolt 14 passing through the lugs or eyelets to 15 form hinge couplings.

At the lower third, the two braces serve as bearing holders for the shaft 6 of a conveying screw parallel to the bottom of the box (slit bottom). The screw-like 20 spirals or coils 7 and 8 are arranged counter to each other from the shield flank to the middle and each with the same pitch. The spiral conveyors 7 and 8 will move or shove the operating material which constitutes the green malt from the sides to the middle of the shield 25 somewhat above the bottom of the box. A soft rubber or elastic strip 2 is provided adjacent the coils 7 and 8 and a trailing outlet 9 is provided at the mid-point, Figure 1, which may be connected to a suction system (pneumatic suction apparatus).

30 Thus by means on the bottom ends of the struts 4 in the form of small wheels 15 which contact and roll on the bottom of the box, there is achieved the result that the conveying spirals 7 and 8 will be maintained a small distance from the bottom of the box. This will ensure 35 the result that a thin layer of green malt will remain under the conveying spirals 6, 7 and 8 in the region of the suction chamber so that the kiln floor slot in the bottom of the box will be tightly covered but will be taken along in a pliant manner at the front to the bottom 40 flexible rubber strip 2 of the lower edge of the shield 1.

In this way there will be provided that a possible 45 excessive suction will be avoided in the air-conditioned chamber in which the apparatus is used.

In accordance with the present invention it is possible 45 to construct the shield 1 in such a way that it has a pleasing and efficient curvature to the upper edge 3 and it can be constructed without difficulties.

The operation of the spiral conveyors by the vertical 50 spindle or chain and gear drive is accomplished in a most economical manner since the green malt will be moved with the greatest ease along the spiral surfaces of the conveyor guided by the curvature of the shield.

In the back position the suction chamber will be held 55 closed by the green malt material. In order to provide for the suction air to carry away, by suction at outlet 9, the green malt directed by the spiral conveyors 6, 7 and 8, it is evident that the shape of the suction chamber is so designed to feed green malt in sufficient quantity.

The structure as shown includes a motor 10 mounted 60 on the outer back surface of the shield 1 by means of its U-shaped carrier 18 which holds the shield in rigid position and by means of a chain with gears, the motor drives the spiral conveyor. A suitable switch box 11 is also secured on the outer surface of the shield and immediately 65 adjacent the motor 10. Also flaps or valves 19 may be provided between the lower flange of the strengthening rib 18 and the soft rubber strip 2, in order to permit the conveying chamber to be easily cleaned and oiled if necessary.

A particularly important advantage is attained by the new apparatus according to the invention in that it is not

expensive or time consuming to transport the apparatus from one malt box ("Saladinkasten-Wanderhaufen") to another in a brewery plant where the apparatus can be connected by means of two eyelets and counter slots 16 to be secured by means of the pins 14 in a very quick method. By the expression ("Saladinkasten-Wanderhaufen") it is explained that it refers to known Saladin boxes which are the germinating boxes in which the green malt is subject to the malting process during the germinating period of approximately 8 days, wherein it is turned over repeatedly (about once a day) by a reversing device. With the Saladinkasten-Wanderhaufen (Saladin box migration heap) the technological principle is changed in such manner compared to the known Saladin method that the green malt is treated according to the Saladin method, but is conveyed after certain intervals of time from one box to another box (migration heap).

It is not necessary to reconstruct present installations to apply the present invention thereto. All present brewery plants are provided with means to couple the elements 14 and to connect an electric line to the switch 11 for the electric motor 10 to drive the spiral conveyors 7 and 8. Heretofore such manual means which may have been used are not comparable with the present structure since they did not include a suction device for the green malt as well as other elements which are illustrated on the drawing. The present invention provides for a fully mechanical operation to remove the green malt by pneumatic means and which is most efficiently accomplished.

I claim as my invention:

1. Apparatus for pneumatically drawing off green malt out of germinating boxes and adapted to be pulled over the entire width of the box comprising a pair of struts having means to removably connect the struts to a traction member, a shield connected to the struts to form an elongated suction chamber and having a lower edge adapted to contact the bottom of the box, said shield having an upper edge adjacent the struts, a shaft having bearing surfaces in the struts and extending longitudinally in the elongated suction chamber parallel to the bottom and longitudinal axis of the box, a pair of spiral conveyors arranged on the shaft to rotate therewith and each having a helical surface extending and terminating at the approximate mid-point of the shaft with the direction of the conveyor flights extending toward each other at the center of the longitudinal shaft, and a suction outlet tube connected to the shield and communicating with the suction chamber at the mid-point of the chamber adjacent the inner ends of the spiral conveyors and at the terminals of the conveyor flights therebetween.

2. Apparatus according to claim 1, in which the bottom edge of the shield is provided with a soft rubber strip to contact the bottom of the box.

3. Apparatus according to claim 1, in which the means to removably connect the struts to the traction member comprises eyelets and removable pins.

4. Apparatus according to claim 1, in which a bracket is provided for each strut connected to the strut and to the shield to brace the shield.

5. Apparatus according to claim 1, in which a bracket is provided for each strut connected to the strut and to

the shield to brace the shield, and in which a cross strut is provided connected to the first-mentioned struts and being U-shaped in cross section, said cross strut rendering the shield rigid.

6. Apparatus according to claim 1, in which the spiral conveyors are arranged in the struts so that they are close to the bottom of the box.

7. Apparatus according to claim 1, in which each strut is provided with a rolled to contact the bottom of the box.

8. Apparatus according to claim 1, in which means are provided in the form of an electric drive connected to drive the shaft and conveyors, and in which means are provided mounted on the outer surface of the shield to support the drive.

9. Apparatus according to claim 1, in which means are provided in the form of an electric drive connected to drive the shaft and conveyors, and in which means are provided mounted on the outer surface of the shield to support the drive, said electric drive including an electric motor and transmission means to the shaft and in which a cover member is provided to protect the transmission means.

10. Apparatus for pneumatically drawing off green malt out of germinating boxes and adapted to be pulled over the entire width of the box comprising a pair of struts having means to removably connect the struts to a traction member, a shield connected to the struts to form a suction chamber and having a lower edge adapted to

30 contact the bottom of the box, said shield having an upper edge adjacent the struts, a shaft having bearing surfaces in the struts and extending longitudinally along the suction chamber parallel to the bottom of the box, a pair of spiral conveyors arranged on the shaft to rotate therewith and each having helical surface flights extending and terminating at the approximate midpoint of the shaft with the helical flights directed toward each other, and outlet means at the midpoint of the shaft and between the two helical flights.

40 11. Apparatus for pneumatically drawing off green malt out of germinating boxes and adapted to be pulled over the entire width of the box comprising a pair of struts having means to removably connect the struts to a traction member, a shield connected to the struts to form a suction chamber and having a lower edge adapted to

45 contact the bottom of the box, said shield having an upper edge adjacent the struts, a shaft having bearing surfaces in the struts and extending longitudinally along the suction chamber parallel to the bottom of the box, a spiral conveyor arranged on the shaft to rotate therewith and having a helical surface, and an outlet tube connected to the shield adjacent the end of the spiral conveyor and communicating with the suction chamber.
